UNITED STATES PATENT OFFICE.

EDWARD ELLETT TALIAFERRO, OF COLORADO SPRINGS, COLORADO.

SHOE-BLACKING MACHINE.

1,266,082.

Specification of Letters Patent. Patented May 14, 1918.

Application filed February 16, 1914. Serial No. 818,995.

To all whom it may concern:

Be it known that I, EDWARD ELLETT TALIAFERRO, of Colorado Springs, in the county of El Paso and State of Colorado, 5 have invented a certain new and useful Improvement in Shoe-Blacking Machines; and I do hereby declare the following to be a full, clear, and exact description of the same, reference being had to the accompanying 10 drawings, forming a part of this specification, and to the figures and letters of reference marked thereon.

This invention relates to machines for blacking and polishing shoes. The machine 15 is of that type designed to perform the several functions while the shoe is held on a suitable rest, and if desired while on the foot of the wearer. The invention is an improvement upon the shoe blacking machine 20 set forth in my prior Patent No. 900,448, dated October 6, 1908.

Objects of the invention are to simplify the mechanism and so construct and arrange the same as to increase its durability and 25 adaptability for the functions to be performed, and at the same time bring the cost of manufacture within reasonable limits; to provide a machine with which the blacking may be effectively distributed to the brushes 30 and applied to the shoe at a number of different points around the same, thus insuring a uniform distribution of the blacking over the surface of the shoe; to provide a machine in which the rotation of the brushes 35 for blacking and polishing the shoe may be increased without increasing the rate of travel of said brushes around the shoe; and to insure a uniform pressure of the brushes against all parts of the shoe without the employment of guiding means for the brushes, 40 other than the shoe itself. Other objects of the invention will appear from the following specification and claims.

The invention consists in certain novel details of construction and combinations and arrangements of parts, all as will be now described and pointed out particularly in the appended claims.

Referring to the accompanying drawings,

Figure 1 is a top plan view of a machine embodying the present improvements, but omitting the casing, motor, toe brush, blacking receptacle and distributor and certain 55 parts which would complicate the illustration, but which are embodied in other views.

Fig. 2 is a side elevation with certain of the parts in section, the section being in substantially a central vertical plane.

Fig. 3 is a perspective view of the mechanism, omitting the shoe rest, brushes, brush carrying spider and gear for rotating the side brushes.

Fig. 4 is a detail plan of the brush and blacking receptacle carrier with means for 65 controlling the supply of blacking to the brush.

Fig. 5 is a sectional elevation of the parts shown in Fig. 4.

Fig. 6 is a detail plan view of the main 70 part of the control mechanism.

Figs. 7 and 8 are a detail plan and sectional elevation, respectively, of the brush carrier spider.

Fig. 9 is a detail perspective of the shift- 75 ing cam and lever for reversing the rotation of the toe brush.

Fig. 10 is a detail sectional elevation of the polish receptacle and distributor.

Fig. 11 is a section on the line 11—11 of 80 Fig. 10.

Fig. 12 is a section through the center of the toe brush.

Like letters of reference in the several figures indicate the same parts.

The machine of the present invention is designed to be mounted in a suitable cabinet, not shown, in such position that a shoe, preferably, but not necessarily, on the wearer's foot, may be placed on a suitable 90 foot-rest and through the manipulation of control mechanism which may be governed by a lever, push button or a coin or token device, inaugurate the operation of the machine to clean, black and polish the shoe 95 placed on the foot rest. The general arrangement of machines of this type, in so far as the features referred to are concerned is well understood in the art and hence in illustrating the present improvements it has 100 been deemed unnecessary to show either the cabinet or the initial control devices, the illustration being therefore limited to the actual operating parts of the machine proper. By reference to Figs. 1, 2 and 3, it 105 will be seen that the mechanism is mounted upon a suitable base or bottom plate at the rear portion of which there is a motor support consisting of right and left hand frames 2 and 3 forming at their upper ends 110 a platform upon which an electric motor of any suitable character may be placed in

proper position for driving a main shaft 37 journaled in suitable bearings 4 on the forward side of the frames 2 and 3. The connection between the motor and shaft 37 conveniently embodies a belt and a driving pulley 72 on the end of the shaft. The shaft 37 is adapted through a worm and worm wheel 1 to drive a countershaft 94 arranged below and at substantially right angles to the shaft 37, where it is supported in suitable bearings or shaft supports 24 and 26. This shaft 94 is in effect the main shaft of the machine, inasmuch as all of the driving connections are taken from it, but through different and independent sets of gearing. One set of gearing operates to rotate the blacking and polishing brushes on their individual axes, another set of gearing operates to move the blacking and polishing brushes bodily around the shoe being operated on at a relatively slow speed, and another set of gearing operates to rotate the toe polishing brush first in one direction and then in the other. All of the movements are carried on simultaneously and provision is made for automatically arresting the movement of the parts when the polishing operation is completed, or, if the brushes become jammed or their movements arrested by a misplaced shoe or other accidental cause.

The foot rest, which is indicated in outline only at A in the accompanying drawings, is mounted on the upper end of a central upright 41, preferably a tubular upright which is anchored in a central base piece or support 40, the said base or support 40 and upright serving also as the supporting journal about which the several mechanisms, including the brush supporting spider and gearing for rotating said spider and brushes and for rotating the brushes themselves, are adapted to rotate. The brush support proper, which is preferably in the form of a three-armed spider 51, is keyed on the upper end of a sleeve 42 journaled on the central support before referred to, preferably through the medium of suitable ball bearings of ordinary construction. The lower end of the sleeve 42 is flanged outwardly to form a support for the attachment of a plurality of gear wheels 45 and 46 and for the attachment of a toe brush cam 44 to be presently described. The gear wheel 46 is a worm gear with which a worm 55 on a secondary shaft 77 is adapted to mesh, said secondary shaft being driven from the shaft 94 through a train of spur gear wheels 70, 73 and 75, whereby the sleeve and brush supporting spider 51 will be given a comparatively slow rotation around the central support below the foot rest.

In addition to the spur gear 70 the shaft 94 is provided with a bevel pinion 48 adapted to mesh with a corresponding gear wheel 65 47 mounted on a secondary bearing sleeve

43 surrounding and preferably journaled on the bearing sleeve 42 before referred to and adapted to carry a relatively large gear wheel 49.

Journaled in each of the arms of the spider 51 is a short vertical shaft 54, upon the lower end of which is mounted a spur gear 50 meshing with the large spur gear 49. Upon the upper end of each shaft 54 there is mounted a pulley 55 adapted for a driving belt leading off to a corresponding pulley on the rotary brush shaft. The rotary brushes 74 are each mounted on vertical shafts journaled in the ends of brush carrying arms 53 and 53^a, said arms being journaled around the bearings in the ends of the brush carrying spider arms 51, whereby they may swing toward and from the foot rest, light springs 53^b (Fig. 7) being provided to hold them pressed inwardly with a very light pressure which does not vary materially as they move outwardly.

The brushes being free to swing on their arms independently of the brush carrying spider, the springs 53^b urge them lightly into contact with the surface of the shoe throughout the entire movement of the spider in carrying the brushes around the shoe. In this construction the shoe itself on the foot rest A acts as a cam for guiding the brushes 95 in their movement, a most important result, for the brushes are made to contact with every kind of shoe, regardless of shape or size, and consequently the machine operates with equal efficiency under all conditions. 100

In the operation of the machine the brush carrying spider is rotated in a direction which will cause its brush carrying arms to trail behind their points of attachment, and thus the brushes are drawn around the shoe 105 placed on the foot rest instead of being pushed around the same, as has been the common practice in machines of the prior art. By drawing the brushes around the shoe there is less danger of a jam occurring 110 such as might alarm the user or even injure his foot, and the action secured is correspondingly softer, lighter and more effective, for it is found with the arrangement shown the shoe may form the sole guide for 115 the brushes, yet they will bear on the shoe with practically a uniform pressure and with no liability to jump in passing around the heel and toe. From an inspection of Fig. 2 it will be seen that one of the brushes 74 is 120 mounted in a plane somewhat higher than the other two brushes, being thus adapted to clean and polish the upper portion of the shoe, or the portion above the sole, while the other two brushes operate more particularly 125 on the lower portion of the shoe and edges of the sole. One of the lower brushes conveniently forms the blacking applying brush or dauber, and in the present machine it is designed that the dauber shall have 130

blacking supplied thereto at periodic intervals, and when in different positions around the foot rest, so as to secure a more even distribution of the blacking. With this object in view, the arm 53^a on which the dauber brush is journaled is provided with a blacking receptacle or cylinder 89 from the forward end of which a discharge duct 90 leads up into proximity to the surface of the brush. This discharge duct 90 is adapted for the reception of a polish distributor tube 82 which distributor tube is a cap-like structure having a series of perforations 82^a therein and a series of peripheral teeth 82^b. The teeth 82^b serve to separate the bristles of the brush 74 and thereby assist in thoroughly impregnating the brush with the polish. It is loosely mounted on the discharge duct and is adapted to be rotated by contact with the periphery of the brush, with the result that polish discharged from the upper end of the duct will be caused to work down the interior of the distributing tube and will be ground and forced out through the perforations therein by the action of the tube in traveling between the duct and surface of the brush.

In order to feed the polish or blacking from the containing cylinder 89, the cylinder is provided with a piston or plunger having a screw threaded stem 89^a working through a threaded opening in the head 89^b and surrounded by a sleeve 84 having thereon a star or toothed wheel 85. The outer end of the sleeve 84 is journaled in a bearing 91 pivotally mounted on the inner end of the brush carrying arm 53^a and the star or toothed wheel 85 is in position to coöperate with an operating pawl 83 mounted on the upper end of a stem 83^a extending vertically through the shaft carrying the gear wheel 50 and pulley 55, all as shown clearly in Figs. 4, 5, 10 and 11. The operating finger or pawl 83 while free to move vertically into and out of position to coöperate with star wheel 85, is caused to rotate in unison with the pulley through the medium of pins 83^b, and the raising and lowering of said pawl or operating finger is controlled automatically through connections to be presently described. The sleeve 84 is provided with an internal square shaft 84^b on which the threaded stem 89^a slides whereby rotary motion of the sleeve 84 is transmitted to the stem and the latter is free to move longitudinally.

A bell crank lever 86 is pivotally mounted in the end of the brush carrying spider arm on which the dauber brush is mounted, one end of said lever extending under the vertical shaft 83^a on which the operating pawl or finger is carried, while the other end of said bell crank lever extends up into position to receive one end of a link 81 usually extending parallel with the spider arm as

shown in Fig. 4, and pivotally connected at its inner end with a pawl or lever 80 mounted on the arm. The pawl or lever 80 is adapted to coöperate with the periphery of a pair of cams 58 and 59 mounted on the central support and having in their peripheries notches 59^a into which the end of the pawl or lever may drop under the influence of a coil spring 81^a, but which may be barred from entering said notches by displacing the cams with relation to each other, so as to close the notches. One of the cams, that numbered 59, is a fixed cam, while the other, numbered 58, is adjustable so as to open or close the notches, and it is preferably actuated automatically so as to open the notches during a portion of each operation of the machine, as for example, when blacking is to be supplied to the dauber and to close the same automatically when the blacking has been supplied, the design of the machine being to supply blacking during one or more revolutions of the brush around a shoe and to utilize the brush as a polishing brush during the remaining revolutions of the brush around the shoe. The automatic operation of the cam 58 is effected through a vertical shaft 88, which at its upper end is connected with the cam through the medium of a transverse pin 87 extending out through slots 87^a in the central support and at its lower end provided with an operating arm or secondary lever 76, extending out through an opening in the base support 40 and connected with one end of a lever 60 through the medium of a link 93, (see Figs. 1 and 3). The lever 60 is periodically oscillated during each operation of the machine by co-operation with a cam 63 to be presently referred to.

The container 89 has been referred to as a blacking container, but it will be understood that any polish or dressing may be employed, black, tan, white, or of any character, all of which are intended to be included by the conventional term blacking. The said container is pivotally mounted on its supporting arms, for which purpose the bearing 91 is hinged to the spider arm and the container is seated in a seat in the arm and held by any ordinary or preferred releasable fastening means. With this construction the whole container may be swung up through a suitable opening in the casing to facilitate refilling.

The spur gear 45 is adapted to mesh with a timing gear 65 mounted on a vertical axis at one side of the central support 40 and provided with a sleeve hub having at its lower end a pinion 66 meshing with a large gear wheel 62, the whole train of gear wheels 62, 65 and 66 constituting a timing train adapted to control the period during which the machine shall run for one operation. The control mechanism embodies a

timing cam 64 mounted on the gear wheel 62 and adapted to rotate in unison therewith. The timing cam 64 is located above the polish control cam 63, before referred to, and the starting and stopping mechanism is adapted to coöperate with the timing cam.

This mechanism is shown in Fig. 3 and in detail in Fig. 6, from which it will be seen that a switch lever 7 pivotally mounted on the base is adapted to coöperate with switch contacts 71, utilized for controlling the current supplied to the electric motor, whereby the mechanism is operated. The switch lever is moved by spring 7^a into position for closing the circuit, and is adapted to be moved on its pivot to open said circuit by means of a catch or cut-out finger 67 pivotally mounted on the end of a time lever 61. The time lever, by reason of the tension of its spring 61^a, normally presses against the periphery of the time cam 64. When the depression in said cam permits, the lever is drawn downwardly in Fig. 6, the hook or catch end 67^a on the cut-out finger engages a projection 67^b on the switch lever and moves said lever to its open position against the tension of its spring 7^a. For holding the switch lever in its open or circuit breaking position it is provided with an arm 7^b having a notch or shoulder 7^c thereon for co-operation with a head 22^a on a starting lever 22 to hold it in its operated position. When the parts are in the position shown in full lines in Fig. 6, the switch contacts are closed and the machine is in operation. Assuming that the cam is rotated to a point where the time lever may move downwardly, such movement will swing the switch lever to open the circuit through the connections aforesaid and will simultaneously release the shoulder 7^c from its engagement with the starting lever 22, and the latter, under the influence of its spring 22^b, will swing back to the position shown in dotted lines, thereby holding the switch lever in its open position. Simultaneously with the movement of the starting lever 22 to the position shown in dotted lines, the catch or cut-out finger 67 will be released from its engagement with the projection 67^b on the switch lever through the engagement therewith of the arm 22^c of the starting lever, leaving the parts in position to have the circuit again established by the simple return of the starting lever to the position shown in full lines. In the latter position, however, with the time lever depressed, the cut-out finger is out of engagement with the projection 67^b, and in order that it may be positively moved back into engaging position when the time lever is elevated, the arm 22^c of the starting lever is provided with a projection 22^d, with which an incline 67^c on the cut-out finger is adapted to coöperate, so as to move the hooked projection 67^a back to the position indicated in full lines.

The starting lever 22 is provided with a pull rod 92 which extends off to any suitable mechanism, or to a hand lever by which the operation of the machine may be inaugurated.

70

For polishing the upper surface of the toe of the shoe a vertically movable rotary toe brush 20^a is mounted on a toe brush spindle 20 journaled to rotate and move longitudinally in a bearing 20^b carried by a forwardly projecting extension of the motor supporting frame. Conveniently, the toe brush spindle 20 is mounted to slide vertically in a sleeve journal 21 directly journaled in the bearing 20^b, the spindle and sleeve journal 80 being connected to rotate in unison. For rotating them, the sleeve journal is provided with a belt pulley 8 around which a belt 8^a passes from a belt pulley 9 on the drive shaft 94. Said belt 8^a in passing between the said 85 pulleys is deflected around idler sheaves or pulleys 13 mounted in clevises 12 having spindles 10 journaled in suitable diagonal bearings in the motor supporting frame. The brush is made vertically movable in 90 order that it may be lifted when the machine is stopped, so as to facilitate the placing of a shoe in position for polishing and also to permit of the passage of the high side polishing brush. In order to accomplish the lifting 95 action for the two purposes mentioned, an automatic lifting mechanism is provided, timed to lift the brush at the moment when the high side polishing brush is passed under the same, and a second lifting mechanism is 100 provided for lifting the brush when the machine is brought to rest after a complete operation.

95

100

110

115

120

125

130

The upper end of the toe brush spindle 20 is provided with a grooved collar 18 with which the forked end of a toe brush lever 6 is adapted to coöperate. This toe brush lever is pivoted intermediate its ends at 14 on a bearing carried by the motor frame and its rear end is connected by a long link 96 with one arm of a bell crank lever or crank arm 68 pivotally mounted near the bottom of the motor supporting frame and having its other arm connected by a long link 95 with a toe brush cam lever 23. The cam lever 23 is pivotally mounted at one end on the base plate with its opposite end projecting in proximity to the starting lever 22 and in position for coöperation with a toe brush cam 44 mounted on the sleeve 42, preferably beneath the work and spur gears 46 and 45, hereinbefore referred to. The form of the toe brush cam 44 is such that during its rotation the toe brush lever 23 will be moved in a direction to effect a pivotal movement of the lever 6, to thereby raise the toe brush, and the timing is such that the toe brush will be raised intermittently and at the proper time to permit of the passage of the high side polishing brush beneath the 130

same. The ends of the bristles of the toe brush preferably ordinarily travel in light contact with the upper portions of the low side polishing brushes and dauber, and from 5 the latter take a certain proportion of the polish which is distributed thereto by the polish distributor, although it is obvious that, if so desired, the upper end of the polish distributor may be provided with an 10 opening at 82° through which polish will feed directly to the toe brush.

As before stated, it is desirable that the toe brush shall be in elevated position when the machine is brought to rest after a complete 15 operation, and this result is effected through an operating connection between the toe brush cam lever 23 and the starting lever 22. The connection is conveniently in the form of a lug 23^a on the starting lever 20 adapted to engage the inner side of the toe brush cam lever, the arrangement being such that the toe brush cam lever is free to follow 25 the configuration of the toe brush cam, but when the starting lever 22 is retracted by its spring 22^b for stopping the machine, as before described, the lug 23^a will draw the toe brush cam lever away from the cam and elevate the toe brush to its greatest height.

In the practical operation of the machine 30 it is found highly desirable to reverse the direction of rotation of the toe brush during each operation so that all parts of the shoe surface will be equally polished, especially where a soft brush is employed. This reversal of rotation is effected by mounting the 35 pulley 9 loosely on the shaft 94 and providing means whereby it may be rotated either by being clutched to the shaft or to a reverse gear, an automatic shifting mechanism 40 being provided whereby the brush will be rotated in each direction during approximately one half of each full operation.

By reference to Figs. 1, 2, 3 and 9 it will be seen that the pulley 9 is provided with 45 oppositely disposed clutch faces 9^a adapted to engage with clutch faces 9^b and 9^c, one fast on the shaft 94 and the other loose thereon. A reverse drive is provided for the loose clutch face 9^c, which may be, for 50 example, the spur gears 9^d and 9^e, the latter being fast on the shaft 77 although any ordinary or preferred form of reverse gearing may be employed. The pulley 9 has a grooved hub for coöperation with the forked 55 shifting lever 146 (see Figs. 1 and 3) the outer end of which projects through the side frame and is bifurcated to form a "fish tail" 146^a. An operating arm or crank 145^a (Fig. 3) on the upper end of an oscillatory shaft 60 145 serves to swing the shifting lever and move the pulley 9 into engagement with either clutch 9^b or 9^c as the case may be, and to lock it in such engagement through the well known locking action of a "fish tail" 65 shifting device. Shaft 145 is connected

through a crank arm and link connection 144 with one arm of an intermediate lever 143 and the latter in turn is connected by a link 142 with a bifurcated lever 140 pivoted on the base and embracing a cam 141 located 70 between the cams 63 and 64 before referred to. The cam 141 is shaped to shift the lever 140 first in one direction and then in the other and through the connections described shifts the pulley 9 to drive the toe brush in 75 one direction or the other. The cam 141 moves in unison with the control cam and reverses the toe brush at the proper time to cause it to rotate approximately half the period in each direction.

The toe brush should operate with a soft action on the shoe and to provide for this it is yieldingly supported on its shaft 20, the preferred form of supporting connection being shown in Fig. 12. Referring to this 80 figure it will be seen that the brush 20^a is held in horizontal position or at right angles to its shaft by a spring K surrounding the shaft and pressing against a center plate L on the brush. The plate L forms a part 85 of or is attached to an annulus M loosely surrounding the shaft and connected through a gimbal joint N with the lower end of the shaft whereby perfect flexibility is provided for the brush to tilt or ride over the shoe 90 and at the same time it is forced to rotate with the shaft.

In operation, the foot is placed on the rest between the side polishing brushes and dauber and the machine is started in operation by a pull on the starting rod 92. By pulling on the starting rod 92 the starting lever 22 is swung to the position shown in full lines in Fig. 6, and as shown in Figs. 1 and 3. This movement permits the switch 100 lever 7 to advance under the influence of its spring 7^a so as to close the circuit to the motor, shown diagrammatically at 100 in Fig. 6, and with the parts in this position the motor becomes effective to rotate the 110 driving shafts 37 and 94, and through the shaft 94 to operate the several brushes. Through the independent trains of gearing leading from the shaft 94 to the large spur gear 49 and to the brush carrying spider 115 51, the side brushes are rotated on their own axes and are given a bodily rotation around the foot rest. In the machine illustrated the brushes rotate around the foot rest approximately 6 revolutions in one entire 120 operation which lasts about one minute and fifty-eight seconds, but the brushes are rotating on their own axes at the rate of about 500 revolutions per minute. This result is attained and made possible by the arrangement of driving gearing, and it will be noted that the large gear wheel 49 revolves at a much higher speed than the brush carrying spider, and the spider and gear travel in opposite directions. The trains 125 130

of gearing employed may be proportioned to rotate the brush around the foot rest or shoe at practically any desired speed and also to rotate the brushes on their own 5 spindles at any speed found necessary to accomplish the desired ends in the most perfect manner. In other words, the two movements are practically independent of each other, and in this respect the machine differs 10 from the prior machines wherein the speed of the brushes on their own spindles could not be changed without correspondingly changing the rate at which the brushes are rotated around the shoe. As the machine 15 continues its operation the time cam 64 rotates until it releases the timing lever 61 and the latter, under the influence of spring 61^a and through the connection formed by the latch 67 moves the switch 20 lever 7, so as to break the motor circuit, the parts then assuming the position shown in dotted lines in Fig. 6.

In connection with the machine, various safety connections are provided for preventing 25 injury should the foot of the person whose shoe is being polished be misplaced in such wise as to block the rotation of the brushes, or if, for any reason the machine becomes jammed so as to stop the movement 30 of the operative parts. Such safety devices embody, for example, the worm sleeve 1, which is held up to its work on the shaft by the coil spring 1^a and in such position is coupled to the shaft by the driving ratchet 36. A very similar arrangement 35 is illustrated in my prior patent before referred to, although the present construction of the device is more efficient in that the driving ratchet will become effective at practically 40 any angular position with relation to the shaft. One end of the worm sleeve is provided with a groove for the upper forked end of a lever 150 pivoted on the side frame and at its lower end engaging 45 a horizontal lever 151 pivoted on the base and having a projection 151^a adapted to coöperate with the switch lever 7. Should the machine jam, a longitudinal 50 movement of the worm sleeve will swing the lever 151 and draw the switch lever 7 away from the contacts thereby interrupting the motor circuit to instantly arrest the machine and prevent any possible injury or alarm 55 to the user who has his foot and shoe on the rest.

Having thus described my invention, what I claim as new and desire to secure by Letters Patent of the United States, is:

1. In a shoe blacking machine, the combination 60 with a foot rest, of a rotary brush carrier mounted on a vertical axis below the foot rest, a plurality of brush carrying arms pivotally mounted on said carrier, brushes journaled in said arms, one of said brushes 65 constituting a dauber, a blacking receptacle

mounted on the dauber brush arm, a discharge duct for said receptacle extending into proximity to the brush, a piston in said receptacle, and means for intermittently advancing said piston, embodying, a driving gear for rotating the brush, and intermittently operating connections intermediate 70 said driving gear and piston.

2. In a shoe blacking machine, the combination with a foot rest, of a rotary brush carrier mounted on a vertical axis below the foot rest, a brush carrying arm pivotally mounted on said carrier to swing toward and from the foot rest, a brush journaled in said arm, a blacking receptacle mounted on 75 said arm and having a discharge duct extending into proximity to the brush, means for rotating the brush on its individual axis, embodying, a driving gear driven at a relatively slow speed, and gearing connections 80 between said driving gear and the brush, and means controlled by said driving gear for intermittently discharging blacking from said receptacle.

3. In a shoe blacking machine, the combination with a foot rest and a rotary brush carrier mounted on a vertical axis below the foot rest, of a plurality of brush carrying arms pivotally mounted on said carrier, brushes journaled in said arms, one of said 95 brushes constituting a dauber, a blacking receptacle mounted on the dauber brush arm, a discharge duct for said receptacle, extending into proximity to the brush, a blacking distributor journaled on said discharge duct 100 and lying in contact with the brush, a piston in said receptacle, and means for intermittently advancing said piston, embodying a driving gear for rotating the brush, and intermittently operating connections intermediate 105 said driving gear and piston.

4. In a shoe blacking machine, the combination with a foot rest and a rotary brush carrier mounted on a vertical axis below said foot rest, of a plurality of brush carrying 110 arms pivotally mounted on the carrier to swing toward and from the foot rest, rotary brushes journaled in said arms, one of said brushes constituting a dauber, a blacking supply duct mounted on the dauber brush 115 arm and extending into proximity to said brush, means for distributing the blacking from said duct onto the brush, means for rotating the brush embodying an operating wheel having an axis coincident with the 120 axis of the pivoted arm, and means for feeding blacking through said duct operated by the brush rotating wheel.

5. In a shoe blacking machine, the combination with a foot rest, of a rotary brush carrier, a brush carrying arm pivotally mounted on said carrier to swing toward and from the foot rest, a brush journaled in said arm, a blacking receptacle, a duct leading from said blacking receptacle into prox- 125 130

imity to the brush, mechanism for intermittently and automatically discharging blacking from said receptacle, and means for rendering said mechanism inoperative during a portion of the operating period of the brush.

6. In a shoe blacking machine, the combination with a foot rest, of a rotary brush carrier, a brush carrying arm pivotally mounted on said carrier to swing toward and from the foot rest, a brush journaled in said arm, a blacking receptacle, a duct leading from said blacking receptacle into proximity to the brush, means for positively discharging blacking from said receptacle, tim-

ing mechanism embodying a fixed and a movable cam having inoperative and operative relative positions, connections between said discharging means and the cams for intermittently operating said discharging means, when the cams are in their operative relative positions, and means for moving said cams into their inoperative relative positions during a portion of the operating period of the brush.

EDWARD ELLETT TALIAFERRO.
